RETAINING SEA WALL

Joel Hurt, North Bay Island, Fla.

Application April 12, 1946, Serial No. 661,718

20 Claims. (Cl. 61—49)

1

This invention is a novel retaining seawall or so-called bulkhead construction, such as is adapted to confine and protect from attrition the earth or fill back of the wall while the wall in turn receives backing from such earth or fill.

Numerous bulkhead or seawall constructions have heretofore been tried and used for sea, lake or river shores but without attaining entire satisfaction. The general object of the present invention is to afford a seawall of straight or curved alignment which possesses the attributes of being strong, rugged and firm in practical use, and highly effective for the intended purposes, while at the same time capable of long life and being of low cost of construction. Other objects and advantages of the present invention will be made to appear in the hereinafter following description of an illustrative embodiment of the invention or will be understood by those conversant with the subject. To the attainment of such objects and advantages the present invention consists in the novel retaining seawall or bulkhead construction, and the novel features of combination, arrangement and detail herein illustrated or described.

In the form herein disclosed the invention comprises in one aspect a combination of structural elements, namely, the wall body consisting of an aligned series of precast concrete slabs whose ends are interlocked, a spaced series of upstanding driven piles, preferably metallic, located contiguously frontwards of the slab series and upon which the slabs are sustained or hung in edge-wise posture, and a series of upstanding concrete pilasters field cast in spaced positions adjoining the front face of the slab series with each pilaster embedding the upper part of one of the upstanding piles; and there preferably being a pile and its embedding pilaster afront each joint between adjoining slabs thereby bridging such joints and solidifying the wall structure; such combination and other features to be more fully disclosed, including a desirable coping element or wall cap.

In the accompanying drawings,

Fig. 1 is an elevational view of a length of seawall embodying the present invention, looking from the water, offshore or front side, and broken away at occasional points to show details of structure beyond; an appropriate mean water line MWL being indicated, as well as a portion of the submerged land or bottom B into which the piles of the wall are driven.

Fig. 2, looking downwardly, is a horizontal sectional view, taken upon the section line 2—2 of

5 Fig. 1, but on a much enlarged scale also used for others of the figures.

Fig. 3 is a horizontal sectional view taken on the section line 3—3 of Fig. 4.

5 Fig. 4 is a vertical sectional view taken on the section line 4—4 of Fig. 6, looking from the front, certain elements being omitted from this figure.

10 Fig. 5, looking from the right, is a vertical sectional view taken on the section line 5—5 of Fig. 1 or Fig. 4, after the pilaster and wall cap have been applied.

Fig. 6 is a vertical sectional view similar to Fig. 5 but taken through a pile on the section line 6—6 of Fig. 1 or Fig. 4.

15 Fig. 7, looking downwardly, is a sectional view taken on the section line 7—7 of Fig. 8; while Fig. 8 is a front elevational view, these two figures showing details of the occasional or periodic expansion joints along the length of the seawall.

20 Fig. 9 is a right hand elevational view partly in section on the line 6—6 of Fig. 1 showing the structural details before the pilaster and coping have been cast, and showing details of the interconnections between the slabs and the piles.

25 Fig. 10 is a diagrammatic top plan view showing the construction of a suitable convex or semi-cylindrical casting form or mold temporarily attached to the wall for the field-casting of the pilasters against the front side of the body or slab-series of the wall.

30 Referring first to Fig. 1, and stated generally, the seawall hereof comprises an aligned series of precast and reinforced concrete slabs 11 which constitute the body of the wall, these being sustained in edge-wise position and having their adjoining upright ends shaped, for example as shown, for mutual fitting or interlocking at the joints to unify the wall; a series of upstanding piles 12 located frontwards of and contiguous 35 to the precast slab series; and a series of upstanding concrete pilasters 13 which are fieldcast, that is, produced at the site, in positions adjoining the front face of the slab series and each pilaster embedding one 40 (adjoining or adjacent) to the precast slab series; and a series of upstanding concrete pilasters 13 which are fieldcast, that is, produced at the site, in positions adjoining the front face of the slab series and each pilaster embedding one 45 of the upstanding piles. As a completing main element the wall usually comprises also a substantially continuous coping or wall cap 14, fieldcast of concrete and embedding the tops of the slabs and pilasters. Preferably the respective concrete elements, the precast slabs and the fieldcast pilasters and coping are unified not only by the casting and setting with bonding of the pilasters and coping directly in place, but by reinforcing tie members extending between the elements.

50 The precast slabs 11 which mutually interlock

and form the wall body are preferably relatively tall, long and thin, for example each slab 7 feet 6 inches high and 10 feet long less $\frac{1}{4}$ inch for jointage and 6 inches thick at the base, tapering to 4.5 inches at the top; these dimensions being merely illustrative and serving also to indicate relatively the dimensions of the other elements of the wall. The wall body or slab series confines behind it the landward earth or fill F, but is suspended in front thereof and does not necessarily extend downwardly into the sea bottom B. However the earth or fill usually extends below the wall slabs and at the front may pile up approximately to the mean low water line MWL forming what may be called a front fill or burn FF. As the slab series extends well below the mean low water line its lower portion is embedded in and protected by and between the back and front fills F and FF.

The upstanding piles 12 arranged contiguously to the wall body at the seaward side are driven downwardly at predetermined intervals, preferably the same as the horizontal length of the slabs, into the sea bottom B, and as largely practiced, the piles are preferably steel railway rails, cut off at their top ends after driving, so that the series of pile tops present a uniform elevation for cooperating with the three concrete elements of the wall.

The pilasters 13 are cast directly in place to stand outward at the front side of the slab series, in positions to embed the upstanding piles and adjacent parts; and while such pilasters might be given different locations at will they, and the piles, are preferably located each frontwards of a joint between two adjoining slabs, thereby to bridge the slab joints and better solidify the wall structure.

The coping 14 in turn is cast directly in place, by suitable front and back forms movable longitudinally during construction progress, and it becomes set and united with the slab and pilaster elements of the wall. In the design shown each length of coping overlies the underneath slab and pilaster, and is formed with a continuous rear flange or skirt 15 depending slightly behind the slab, and a deeper front flange 16, shown concave to constitute an extended fillet at the under side of the coping, and reaching well down along the upper face of the slab.

The fieldcasting of the pilasters 13, which is done partially below water, requires a special mold or form, and in Fig. 9 there is shown a semicylindrical upright mold or matrix 17 set directly against two adjoining slabs, and there suitably secured as by fastening bolts 18 engaging in threaded recesses or anchor sockets 19 formed in the slabs. The mold or form 17 may be open below as well as above when reaching substantially to the front fill or sea bottom; otherwise its lower end may be closed during casting. An advantage of the open-bottom mold form is that the concrete can issue and spread somewhat frontwardly and rearwardly before setting within the front and back fill and thus produce a hard bulge underlying the slabs and surrounding the piles below the slab level. This underneath extension or bulge 20 is roughly indicated in Fig. 6, mushroomed into the filling material F and FF.

In regard to wall jointage there are shown, first, regular joints 21 between adjacent slabs, which may but need not be filled with a bonding or other suitable joint material; and when no packing is introduced during the placing of

the slabs, there may be entry into the crevices of soup or grout during the forming of the pilasters. Secondly, there are periodic special expansion joints 22 between slabs, for example at the end of every fourth slab, or at 40 foot spacing intervals, these being somewhat wider than the regular joint spaces and being filled with resilient or compressible packing material which can allow for a practical degree of thermal expansion and contraction. Corresponding in position with the expansion joints 22 between slabs there are shown expansion joints 23 between disconnected lengths or forty foot sections of coping, so that the unified slabs and coping may jointly partake of the same expanding and contracting movements at the same points. To complete the expansion jointage there is provided, as shown in Figs. 7 and 8, an expansion joint 24 between an unconnected half of the contiguous pilaster and the coping section thereabove; with an additional expansion joint 25 between such unconnected pilaster half and the adjacent wall slab 11, these permitting relative longitudinal sliding motions as is necessary. The remaining structure shown in Figs. 7 and 8 will be hereinafter described.

Referring further to the prefabricated wall slabs 11, their reinforcement is indicated as a wire mesh comprising a system of horizontal and vertical bars 27 and 28. In addition to such main reinforcement each slab is shown as provided with certain other embedded or partly embedded elements. Among these are wire loop members 29, protruding from the front side of the slab above the middle thereof and near each end, which loops later become embedded in the pilasters thus affording interlocking means between pilasters and slabs supplementing the interbonding thereof. Each of the slab front loops 29 may be used for tying the slabs to the piles, before the pilasters are cast, but their primary purpose is to afford connecting means or protrusions by which the slabs are sustained or suspended in edgewise posture, by hangers 30, from the top portions of the piles. Thus each hanger 30 is shown as an inclined double hook member, with its upper hook extending frontwardly and engaging over the top of the pile flange or extension 42 to be described, while its lower hook extends laterally in engagement with the protruding wire loop 29. In this way each slab is securely mounted by the loose hangers 30 at its two ends, receiving support from the upright piles in preparation for the casting of the pilasters and coping sections.

Before the pilasters are cast, to embed the piles and hangers adjacent to the front faces of contiguous slabs, the slabs are preferably tied to but slightly spaced from the piles by suitable tying means. Thus, for example, near the upper part of each slab at each end a wire tie 32 is provided, engaging the protruding loop 29 and passing around the pile, and the tie may be tightened by having its ends bent into holding engagement with the adjacent loops of two successive slabs, or by twisting its ends or otherwise. Near the lower part of each end of each slab is shown a second protruding loop 31, and from two adjacent lower loops extends a second wire tie 32, likewise carried around the pile and twisted or securely fastened, as by hooking its two ends to the respective loops, as shown. Each hung slab thereby, at upper and lower points at each end, is tied to the previously driven piles; but it is preferably spaced somewhat away from the piles, there being shown for this purpose upper spacer

blocks 33 near to or somewhat higher than the protruding loops 29 and lower spacing blocks 34 near or below the lower protruding loops 31. These upper and lower spacers, at each end of each slab, may be composed of any desired material, being preferably simple preformed blocks of concrete, insertable in position at the time the slabs are being tied to the piles in front of them, and the subsequent formation of the pilasters serving to embed the spacer blocks and wire ties along with the slab loops, the hangers and the piles.

Each slab additionally may be provided, preferably near each end of its upper portion, with a through hole 36, formed for example by coring, or later by punching, to receive the tie-back rod 45 to be further described; and each slab at its extreme top is provided with one or several protruding wire loops 37, as of hairpin form, partly embedded and locked in the slab, its upstanding end or loop being in position to become embedded in the overlying coping or wall cap 14 which thereby becomes better tied to and unified with the body of the wall.

The aligned piles 12 are shown of the form of railway rails, each with a base flange or plate portion 40 connected by a web with an enlargement or ball 41. In cutting or burning off the tops of the series of piles to a uniform height, preferably the web and ball are cut somewhat lower than the flange, so that several inches of flange remain as an upstanding flat pile-end 42, the top edge of which flange may be formed with a pair of notches 43 to receive the top hooks of the two hangers which depend from each pile top for the suspension of two contiguous slabs. The upstanding pile ends are also formed with holes 44 through which may be extended the back tie rods 45.

Each of the tieback rods 45 is shown as extended through one of the holes 36 in a slab, preferably punched at the time, and thence through the hole 44 near the top of an adjacent pile. The rod has a prolonged thread at its front end, receiving a holding and tightening nut 46, which may be turned to draw rearwardly or landwards the upper end of the pile and along therewith the adjacent slabs, by way of truing up the seawall. The tie rod 45 may extend backwardly at a downward slant as is customary and at its rear end may be engaged with an anchor member or deadman 47, passing through a hole in such anchor piece and at its rear end carrying an enlarged head or preferably a back nut 48, which may be tightened as required, these parts to be buried underground or confined by the portion of the filling which is placed behind the seawall during the progress of its erection, before the tightening of the front nut 46 and the casting of the pilaster.

There was previously described the provision of expansion joints at suitable intervals, such as at the end of each fourth slab; the joints 22 and 23 extending through the slab part of the wall and the overlying coping, permitting thermal expansion and contraction, without which the wall body might buckle and the pilasters crack. It was explained that the pilaster at such a joint is permitted to become bonded to only one of the contiguous slabs which meet at the expansion joint, having a sliding relation with the other slab and with the coping section thereabove at the joints 24 and 25. This creates a local situation requiring provision for longitudinal play as between the pilaster and its unbonded half, and the ends 75

of the slab and coping adjacent thereto; the hanger extending from the top of the embedded pile downwardly and rearwardly to the slab, which has a minor but appreciable movement of expansion and contraction relative to the pile and pilaster.

To afford play for these relative movements, the usual hanger 30 is replaced by a special linked or chain hanger 50, which as shown in Figs. 7 and 8, comprises an upper hanger link 51 and a lower hanger link 52, these flexible combined links extending from the pile top 42 to the protruding loop 29 of the slab. Since the embedding of these parts in set concrete would render them rigid, an internal non-rigid volume 53 is provided, within the pilaster volume, which is free of set concrete and is in nature of a cavity opening onto the slab surface, preferably filled however with a pliant or workable mass 53 as of putty, soft rubber, or other jelly-like, elastic or plastic material, which is applied and roughly modeled to embed wholly the lower link and portions of the upper link and slab loop beyond. During expansion and contraction this arrangement of the lower link or hanger length permits a sufficient extent of relative movements between the low protruding loop 29 carried by the slab and the high hanger link 51 carried by the pile to permit relative sliding and prevent appreciable wear, breakage or other damage adjacent to the expansion joints of the seawall. After the wall is installed the cavity filling material, which was necessary during pilaster casting, is no longer essential and can safely be permitted to disappear by attrition or otherwise.

A preferred method of erecting the seawall comprises the following steps. The slabs are prefabricated or precast and consist of reinforced concrete, with the protrusions 29, 31 and 37 being embedded during casting and later taking part in the further construction steps. The slabs have complementary ends shaped for interengagement, and are formed with holes 36 preferably drilled later to receive the tieback rods. The metal piles, which have to carry the entire load of the wall, are driven into the sea bottom to a suitable depth and to the required bearing, and at proper intervals, such as 10 foot spacing, along the desired contour of seawall, allowing for example a space of the order of 2 inches between the row of piles and the slab positions. The piles are then severed or burned off to a uniform height and part of the web and head of each pile removed near the top end to provide the upstanding flange 42, in which the notches 43 and rod hole 44 are burned or bored. The slabs are thereupon set up and suspended in alignment from the pile tops, by means of the hangers, the latter being hooked at their lower ends into the protruding slab loops 29. It is understood that the erecting work is carried progressively along the seawall, and that each slab is hung from the piles by both ends of the slab as described. Before casting the pilasters each slab is spaced away from the two adjacent piles by the spacer blocks 33 and 34, while being tied to the piles by the upper and lower wire ties 32. Preferably the tieback rods are at this stage positioned and secured in the manner described, at least one such tie rod for each metal pile. Some tightening up of the tie rods at their back or forward ends, may now be performed. A large part of the fill may be placed at this time, filling up to a point above the anchor plates 47 the depression between the slab series and the solid earth behind. The final

shortening of the tie rods may now be performed to pull the slabs into alignment.

After next cleaning out all dirt and foreign material between the slabs and piles, the pilasters are cast in their forms in a manner to become bonded to and interlocked with the slabs, with a pilaster preferably in front of each vertical wall joint; the poured concrete filling the entire pilaster volume including the space provided between piles and slabs. The concrete is poured into the pilaster form, preferably in excess, so as to fill the mold and to spread or bulge therebelow to afford a more secure and solid anchorage. The placing of the concrete is continued until the pilaster extends upwardly substantially flush with the tops of the slabs as best seen in Fig. 6. This concrete embeds the piles and the protruding loops 29 and 31, the spacing blocks 33 and 34, the adjacent tie wires 32 and the hangers. The pilasters become bonded to the slabs, with the described exception that at periodic expansion joints the pilaster is permitted to become bonded to only one of the two contiguous slabs; and as already stated, at the expansion joint position one of the two slab hangers is of the special form shown at the righthand side of Figs. 7 and 8, this being embedded in a solid mass of soft non-setting material or putty prior to the pouring of the pilaster. When the pilasters have become set or sufficiently stiffened their casting forms are removed. The coping forms or molds and steel reinforcement are then applied, progressively along each length of the seawall, and the coping concrete is poured between the front and rear mold members, shaped to correspond with the coping contour shown in Figs. 5 and 6. The coping thus is caused to embed the top ends of the slabs and pilasters and to extend upwardly to a suitable thickness, preferably with a flat top, the coping being firmly held not merely by bonding but by the protruding hairpin loops in the slabs, and similar interlocking members that may be introduced into the top ends of the pilasters. Also the coping may contain reinforcement 38 laid in place during casting. When the coping forms are removed, along each progressive section of the seawall the construction thereof is completed, and the filling of the space behind the wall may be completed, for example up to the top level of the coping.

What is claimed is:

1. In a retaining seawall or bulkhead, in combination, an aligned series of precast interlocking concrete slabs sustained in edgewise posture and constituting the body of the wall, a spaced series of upstanding driven piles located contiguously frontwards of the aligned series of slabs and upon which piles the slabs are suspended, and a series of upstanding concrete pilasters fieldcast in spaced positions adjoining the front face of said slab series, and with each pilaster embedding the upper portion of one of said upstanding piles.

2. In a retaining seawall, in combination, an aligned series of precast concrete slabs sustained in edgewise posture, a spaced series of upstanding driven piles located contiguously frontwards of the joints between the aligned series of slabs, hangers by which the slabs are suspended from the upper parts of the piles, and a series of upstanding concrete pilasters fieldcast in spaced positions adjoining the front face of said slab series, and with each pilaster located frontwards of a joint between two adjoining slabs and bridging such joint and embedding the upper portion of the adjacent upstanding pile as well the hangers

by which the slabs are suspended from the piles.

3. The seawall as in claim 1 and wherein each of the fieldcast pilasters is formed with a concrete spread or bulge depending at its submerged lower end and there extending laterally and below the slab series within the sea bottom or earth fill.

4. The seawall as in claim 2 and wherein each slab for each hanger is formed with a front protrusion or metal loop engaged with the hanger lower end while the hanger upper end overhangs the pile top; the pilaster concrete embedding all these parts.

5. The seawall as in claim 1 and wherein the piles are located afront the joints between the slabs and extend up to a predetermined uniform height; and the suspended slab tops extend up to a predetermined height somewhat higher than the pile tops; and the pilasters extend up higher than the pile tops and substantially even with the slab tops.

6. The seawall as in claim 1 and wherein the slabs, piles and pilasters have interconnecting means as follows: the slabs carry front protrusions or metal loops embedded in the pilasters, while the pilasters embed the piles and are bonded to the slabs.

7. The seawall as in claim 2 and wherein the slabs, piles and pilasters have interconnecting means as follows: the slabs carry front protrusions or metal loops embedded in the pilasters, while the pilasters embed the piles and are bonded to the slabs.

8. The seawall as in claim 1 and wherein the slabs, piles and pilasters have interconnecting means as follows: the slabs carry front protrusions or metal loops embedded in the pilasters; and there are ties or wires extending from such protrusions and secured to the piles.

9. The seawall as in claim 1 and wherein the slabs, piles and pilasters have interconnecting means as follows: the slabs carry front protrusions or metal loops embedded in the pilasters; and there are ties or wires extending from such protrusions and secured to the piles, and spacers or blocks inserted between the slabs and piles forming clearances occupied by the pilaster concrete.

10. The seawall as in claim 2 and wherein the slabs, piles and pilasters have interconnecting means as follows: the slabs carry front protrusions or metal loops embedded in the pilasters; and there are ties or wires extending from such protrusions and secured to the piles, and spacers or blocks inserted between the slabs and piles forming clearances occupied by the pilaster concrete.

11. A seawall as in claim 1 and wherein is a coping or wall-cap fieldcast atop the slabs and pilasters and embedding and bonded to the tops thereof.

12. A seawall as in claim 2 and wherein is a coping or wall-cap fieldcast atop the slabs and pilasters and embedding and bonded to the tops thereof.

13. A seawall as in claim 1 and wherein is a coping or wall-cap fieldcast atop the slabs and pilasters and embedding and bonded to the tops thereof, with interconnecting protrusions extending up from the slabs and/or pilasters and embedded in the coping.

14. A seawall as in claim 1 and wherein is a coping or wall-cap fieldcast atop the slabs and pilasters and having depending flanges at front

and back, the front flange extending well down along the slab faces and being concave.

15. The seawall as in claim 11 and wherein are periodic expansion joints of substantial width between slabs; the coping being in prolonged sections with wide joint spaces therebetween registering with the slab expansion joints; and the contiguous pilaster having its first half joined to one slab but its second half free of the contiguous slab whereby its free second half can slide relatively along the second slab and connected coping during expansion and contraction.

16. The seawall as in claim 12 and wherein are periodic expansion joints of substantial width between slabs; the coping being in prolonged sections with wide joint spaces therebetween registering with the slab expansion joints; and the contiguous pilaster having its first half joined to one slab but its second half free of the contiguous slab whereby its free second half can slide relatively along the second slab and connected coping during expansion and contraction.

17. In a retaining seawall, in combination, aligned series of precast concrete slabs sustained in edgewise posture, a spaced series of upstanding driven piles located contiguously frontwards of the joints between the aligned series of slabs, hangers by which the slabs are suspended from the upper part of the piles, and a series of upstanding concrete pilasters fieldcast in spaced positions adjoining the front face of said slab series, and with each pilaster located frontwards of a joint between two adjoining slabs and bridging such joint and embedding the upper portion of the adjacent upstanding pile and as well the hangers by which the slabs are suspended from the piles; the slabs being spaced in groups with substantially closed joints between the slabs of each group, but with periodic open or expansion joints of substantial width between slab groups; and the contiguous pilaster at each expansion joint having its first half unitary with one contiguous slab but its second half free of the next adjacent slab whereby its free second half can slide relatively along the second slab during expansion and contraction.

18. In a retaining seawall, in combination, aligned series of precast concrete slabs sustained in edgewise posture, a spaced series of upstand-

ing driven piles located contiguously frontwards of the joints between the aligned series of slabs, hangers by which the slabs are suspended from the upper part of the piles; and a series of upstanding concrete pilasters fieldcast in spaced positions adjoining the front face of said slab series, and with each pilaster located frontwards of a joint between two adjoining slabs and bridging such joint and embedding the upper portion of the adjacent upstanding pile and as well the hangers by which the slabs are suspended from the piles; and a coping fieldcast atop the slabs and pilasters and embedding and bonded to the tops thereof; the slabs being spaced in groups with substantially closed joints between the slabs of each group, but with periodic open or expansion joints of substantial width between slab groups; the coping being in prolonged sections with wide joint spaces therebetween registering with the slab expansion joints; and the contiguous pilaster at each expansion joint having its first half unitary with one contiguous slab but its second half free of the next adjacent slab whereby its free second half can slide relatively along the second slab and connected coping section during expansion and contraction.

19. A seawall with expansion joints as in claim 17 and wherein the slab hanger at such second-free pilaster half is a flexible or linked hanger, and is located within a cavity or recess formed in the pilaster whereby to provide play during expansion and contraction.

20. A seawall as in claim 1 and wherein is a back-stay or tie-back extended from the upper part of the wall rearwardly to an embedded anchor, with its front end secured to the pile top.
